(Continued)Primary Examiner — Phillip S Hyder(74) Attorney, Agent, or Firm — Irina Hass(57) CLAIM

The ornamental design for a utility knife, as shown and described.

DESCRIPTION

FIG. 1 is a front perspective view showing the new design for a utility knife;

FIG. 2 is a front view thereof;

FIG. 3 is a rear view thereof;

FIG. 4 is a top view thereof, the bottom view being a mirror image thereof;

FIG. 5 is a left side view thereof;

FIG. 6 is a right side view thereof; and,

FIG. 7 is a rear perspective view thereof.

The portions of the utility knife shown in broken lines form no part of the claimed design.
